TEXTILE FABRIC

Joseph Byrnes, Cambria Heights, N.Y., assignor to Tiffany Fabrics, Inc., New York, N.Y., a corporation of New York

Filed Aug. 1, 1963, Ser. No. 76,071

Term of patent 3½ years

(Cl. D92—1)

The figure is a plan view of a textile fabric, showing my new design.

The design unit is contained between the dashed lines, which unit is repeated in regular succession as indicated by the extensions beyond the unit boundaries.

I claim:

The ornamental design for a textile fabric, as shown and described.
